UNITED STATES PATENT OFFICE

ROBERT J. McNITT, OF NIAGARA FALLS, NEW YORK, ASSIGNOR TO ROESSLER & HASS-LACHER CHEMICAL COMPANY, OF NEW YORK, N. Y., A CORPORATION OF NEW YORK.

ELECTROLYTIC PROCESS.

1,027,495.

Specification of Letters Patent.

Patented May 28, 1912.

Application filed September 25, 1909. Serial No. 519,511.

To all whom it may concern:

Be it known that I, ROBERT J. McNITT, a citizen of the United States of America, residing at Niagara Falls, in the county of 5 Niagara and State of New York, have invented a certain new and useful Improvement in Electrolytic Processes, of which the following is a specification.

My invention relates to a new and useful 10 improvement in electrolytic processes and the object of the invention is to provide a means for regulating and controlling the temperature of the electrode substance.

My invention relates more specifically to 15 those electrolytic processes in which it is desired to absorb and retain one or more of the products of the electrolysis in the electrode substance. In carrying out such processes it is often found that when the temperature of the electrode substance rises beyond certain limits, said substance refuses to take up any further products of electrolysis and may even give off part or all of 20 said products already absorbed. It has been proposed to overcome this difficulty in 25 part by adding to the electrolyte certain fluxing agents which enable electrolysis to take place at lower temperatures. This remedy has two disadvantages: First, the 30 addition to the electrolyte of fluxing agents brings increased cost and complexity into the process. Second, in case the temperature does rise beyond the limit desired, owing to improper manipulation, impurities or 35 other causes, it is evident that the presence of fluxing agents would be of no benefit, since the products of electrolysis recombining in the electrolyte produce more and more heat, with attending rise in temperature. It 40 has further been proposed to overcome the difficulty stated by circulating cooling liquids around the electrolyte, as by means of external waterjackets and thus controlling temperature. This remedy has the disadvantage of adding danger and complexity 45 to the process and furthermore does not directly reach the seat of the trouble since it removes heat from the overheated electrode substance by cooling the electrolyte. Hence 50 the electrolyte must be maintained at a lower temperature than the electrode substance, thus offering a higher electrical resistance which under constant flow of current results in the production of more heat

units which must also be dissipated. Furthermore, the remedies suggested depend largely upon very careful manipulation for success in operation, and in case the temperature does rise beyond the desired limits, it is customary to shut off the power, clean out 60 the electrolyte from the cell and start over again.

My invention consists in regulating and controlling the temperature of the electrode substance by cooling the same directly, *i. e.* 65 withdrawing heat directly from the electrode substance and thus reducing its temperature. As the electrode substance is usually a metal or mixture of metals having a high capacity for conducting heat, it is 70 easy to cool the same or withdraw heat from the same, by bringing said substance into contact with cooling surfaces either by circulating the substance over the cooled surface, or by circulating some cooling agent 75 through the substance in suitable coils, or otherwise. By this method it is possible to regulate and control the temperature of the electrode substance and at the same time maintain a higher temperature in the electrolyte, thus lowering its electrical resistance with resulting economy of power as 80 well as rendering the process more simple in operation.

In the following I have described, in connection with the accompanying drawings, 85 two means of carrying out my invention, the features thereof being more particularly set forth hereinafter in the claims.

Figure 1 is a vertical sectional view of an 90 electrolytic cell showing one means of carrying out my invention and Fig. 2 is a similar view showing another means of carrying out my invention.

I shall describe the drawings with reference to the application of my method to the well known process of electrolyzing sodium chlorid and absorbing the metallic sodium in a cathode of lead, similar numerals of reference indicating similar parts throughout the 100 several views.

In the drawings, 1 indicates an electrolytic cell having walls 2, 2 and a bottom 3, preferably of cast iron.

4 is a magnesia lining to protect the walls 105 of the cell, the magnesia lining preferably extending down a short distance into the cathode metal as shown.

5 is a partition extending from side to side of the cell, leaving spaces 6 and 7 at either end between the end of the partition and the walls 2, 2 of the cell, the partition 6 thus forming a channel 8 between itself and the bottom 3 of the cell, the channel being in free communication with the upper part of the cell at either end of the partition.

9, 9 indicates the anodes of carbon, graphite or other suitable material connected by 10 means of a wire 10 with a source of suitable electric energy (not shown).

11 represents a stirrer blade on shaft 12 driven by gear 13 actuated by any convenient source of power, the function of the stirrer blade 11 being to cause a circulation of the cathode metal 14 from the upper part of cell 1 through opening 6 channel 8 and opening 7, back again into the upper 20 part of the cell 1.

15 is an electric contact making electrical connection with the electrode substance.

16 is a coil of suitable pipe extending into channel 8 and adapted to be connected with 25 a suitable supply for circulating water, molten lead or other suitable cooling agent through it, so that as the cathode metal is caused to circulate over and around the same by means of the circulating device 11, 30 it will give up a portion of its heat.

17 is a coil adapted to rest on partition 5 and to extend through the electrode substance, said coil being in connection with a suitable source of supply for circulating 35 water, molten lead or other cooling agent through the same and thus withdrawing heat from the electrode substance. The coil 17 is shown in a corrugated form so as to present a greater cooling surface to the 40 electrode substance. The cell is made airtight by means of a suitable cover 18, preferably of asbestos, provided with an opening 19 for the escape of chlorin. This may be conducted to any suitable receptacle 45 for further use. Suitable openings (not shown) are also provided in cover 18 for charging the cell.

In the operation of the device it is well known that if the temperature of the cathode rises beyond certain limits, the limits 50 depending upon the proportion of sodium in the cathode material, the cathode material will refuse to absorb more sodium readily and may even give off 55 part of that already absorbed. Now as the temperature of the sodium lead alloy in the cell is approximately 800° centigrade and the temperature of molten lead is 325° centigrade, it is obvious that the 60 circulation of the molten lead through the cathode material or sodium lead alloy will reduce the temperature of the cathode material. The circulation of water or other cooling substance through the coils 16 or 65 17 have a similar effect.

It is unnecessary to further explain the operation of the process than to state that when the cell is in operation, the molten lead cathode will absorb sodium to form sodium lead alloy in the well known manner, the chlorin passing off, the sodium lead alloy acting as the cathode substance being circulated through channel 8 by the means described, and passing over, around or in contact with coils 16 or 17, which coils are 70 maintained at a temperature less than the temperature of the sodium lead alloy by means of the circulation of cooling fluids through them, the result of the operation being the cooling of the electrode substance, 75 in this case, sodium lead alloy, directly without at the same time cooling the electrolyte or increasing the electrical resistance.

It is obvious that many different kinds of 80 apparatus may be adapted to carry out the process described and that the process may be used in connection with electrolysis of other compounds than sodium chlorid and I do not restrict myself to any of the details as shown and described.

What I claim and desire to secure by Letters Patent is:

1. An improvement in electrolytic processes which consists in maintaining the temperature of the electrode substance at a point most favorable for electrolysis by causing said substance to circulate adjacent to a cooling surface.

2. An improvement in electrolytic processes which consists in maintaining the temperature of the electrode substance at a point most favorable for electrolysis by causing said substance to circulate over a cooling surface.

3. An improvement in electrolytic processes which consists in maintaining the temperature of the electrode substance at a point most favorable for electrolysis by causing said substance to circulate adjacent to a cooling surface supplied with a separate cooling agent from without the cell.

4. An improvement in electrolytic processes which consists in maintaining the temperature of the electrode substance at a point most favorable for electrolysis by causing said substance to circulate over a cooling surface supplied with a separate cooling agent from without the cell.

5. An improvement in electrolytic processes which consists in maintaining one of the electrodes in a liquid condition and in maintaining the temperature of said liquid electrode substance at a point most favorable for electrolysis by bringing said substance and a cooling device into contact with each other.

6. An improvement in electrolytic processes which consists in maintaining one of the electrodes in a liquid condition and in

maintaining the temperature of said liquid electrode substance at a point most favorable for electrolysis by bringing said substance and a cooling device supplied with 5 a separate cooling agent from without the cell into contact with each other.

In testimony whereof I have signed this

specification in the presence of two subscribing witnesses.

ROBERT J. McNITT.
